(57) **CLAIM**

The ornamental design for a transmission, as shown and described.

DESCRIPTION

FIGS. 1 and 2 are respectively perspective front and rear views of the transmission according to the invention.

A particular peculiarity is the shape of the transmission, in particular the shape of the housing.

FIG. 3 is a top view of the transmission of FIG. 1, highlighting the connecting elements for carrying the connecting lines.

FIG. 4 is a bottom view of the transmission of FIG. 1.

FIG. 5 is a right side view of the transmission of FIG. 1 and is the same as the left side view; and,

FIGS. 6 and 7 are respectively front and rear views of the transmission of FIG. 1.

The features shown in dotted lines in FIGS. 1-7 do not form part of the design.
